UNITED STATES PATENT OFFICE.

GEORGE A. WHEELER, OF WAKEFIELD, MASSACHUSETTS.

PIANISSIMO DEVICE.

No. 922,828.

Specification of Letters Patent.

Patented May 25, 1909.

Application filed April 13, 1908. Serial No. 426,786.

To all whom it may concern:

Be it known that I, GEORGE A. WHEELER, a citizen of the United States, residing at Wakefield, in the county of Middlesex and 5 State of Massachusetts, have invented certain new and useful Improvements in Pianissimo Devices, of which the following is a specification.

This invention relates to piano actions, 10 and more particularly to a pianissimo device for grand-pianos. The object of the invention is to provide a device of this kind which is simple in construction, positive in action, and also one which retains a better balance 15 of the key.

In the accompanying drawing, Figure 1 is a side elevation of a grand-piano action showing the application of the invention. Fig. 2 is a similar view showing the position of the 20 parts with the soft-pedal depressed.

Referring specifically to the drawing, 5 denotes the key of a grand-piano action, 6 is the hammer, 7 the hammer rest-rail, 8 the capstan, and 9 the wippen. These and the other 25 parts of the action are constructed and arranged as usual and need no further description.

The rail 7 is operated by the usual lifter 25 which is connected to the soft pedal (not 30 shown).

At 10 is indicated a rail which extends longitudinally through the piano in front of the action, and is pivoted at 11 to arms 12 projecting from the action-bracket 13. The 35 pivotal connection is such that the rail may be swung toward the action. To the action-bracket is fulcrumed at 14 a bell crank-lever, one branch 15 of which is connected to the rest-rail 7. The other branch 16 of the lever 40 is adapted to engage the upturned end of an arm 17 secured to and projecting from the rail 10. On the rail 10 is also mounted a flange 18 to which is pivoted at 19 a wedge-shaped block 20 which extends between 45 abutments on the key and the wippen, respectively, the former being a block 21 which is mounted on top of the key, and the latter being a capstan 22 which depends from the wippen. The block 21 and the capstan 22 50 are located in front of the capstan 8. To the flange 18 is secured a spring 23 which presses with its free end on the wedge 20 and holds it down on the block 21 to preserve a uniform balance of the key, to prevent chattering of 55 the wedge, and to throw the rail 10 back to

its normal position when the soft pedal is released.

The normal position of the parts herein described is shown in Fig. 1. In this position the point or narrow part of the wedge 20 fits 60 between the block 21 and the capstan 22, and the movement of the key is communicated to the wippen 9 by the capstan 8. With the wedge in this position the position of the action is not changed, and as the wedge is piv- 65 oted it rises and falls freely with the key and the action and therefore does not affect the touch. When the soft-pedal is depressed, the rail 7 is raised, and as the bell crank-lever is connected thereto it swings on its ful- 70 crum 14. The branch 16 of the lever then engages the upturned end of the arm 17 and tilts the rail 10 in a direction to push the wedge 20 forwardly. When the thick portion of the wedge enters between the block 75 21 and the capstan 22, the wippen swings up- wardly on its pivot 24 and the entire action is raised which shortens the travel of the hammer and decreases the impact. The capstan 8 is now no longer in contact with 80 the wippen, and while playing, the motion of the key will be transmitted to the wippen by the block 21, the wedge 20, and the cap- stan 22.

When the soft-pedal is released, the weight 85 of the rail 7 swings the bell crank-lever on its fulcrum in a direction to disengage its branch 16 from the upturned end of the arm 17 whereupon the rail 10 is tilted back by the pressure of the spring 23 on the wedge 20 and 90 the latter is withdrawn and restored to its normal position with its point or narrow end between the block 21 and the capstan 22. Upon withdrawing the wedge as stated, the 95 action drops to its normal position.

By the arrangement of parts herein de- 95 scribed a simple and effective pianissimo de- vice is had which can be readily applied to the ordinary grand-piano action, and by its employment lost motion is eliminated and 100 the action will properly respond to the touch while playing pianissimo passages.

I claim:

1. In a grand piano-action, the combina- 105 tion of a key, a wippen, abutments on the key and the wippen, a hammer rest-rail, a movable supporting member, a wedge con- nected to said member and projecting be- 110 tween the abutments, and a bent lever piv- oted above the wippen and having one arm

connected to the hammer rest rail and the other arm connected to the said supporting member.

2. In a piano-action, the combination of a key, a wippen, abutments on the key and the wippen, a pivoted supporting member, a wedge pivoted to said member, and projecting between the abutments, a spring fastened to the supporting member and press-

ing on the wedge, and means for actuating 10 the supporting member to advance the wedge between the abutments.

In testimony whereof I affix my signature in presence of two witnesses.

GEORGE A. WHEELER.
